FIDELITY CONTROL CIRCUITS

George Victor Dowding, London, England, assignor to Radio Corporation of America, a corporation of Delaware

Application November 16, 1933, Serial No. 698,311
In Great Britain November 16, 1932

7 Claims. (Cl. 250—20)

The present invention relates to improvements in wireless receiving circuits, and is more particularly concerned with receiving circuits employing tone control arrangements.

It is well known that in a selective wireless receiver employing reaction whereby the degree of selectivity may be regulated the passage of a modulated wave through the receiver is accompanied by a higher attenuation of the high frequency components than of the low frequency components. This high-note loss is compensated for by the employment of an amplifier stage designed to accentuate the high notes more than the low notes. This method of tone correction, however, does not take into account the variation in the amount of reaction or degree of selectivity employed when receiving different stations. For instance, when receiving signals from a local station normally no reaction is employed and, consequently, the high note loss is that if signals were being received from a distant station. High note compensation will, however, take place to the same extent as if signals were being received from a distant station and distortion will consequently take place.

It is the object of the invention to obviate the above mentioned disadvantage and, to this end, provision is made of a circuit such that when receiving signals from a local station, when normally no reaction is employed, that is, when the circuit is broadly tuned and is not highly selective, the high note loss is increased to bring it to the same level as when signals are received from a distant station. Tone correction is then applied and distortion will not take place.

In the accompanying illustrative drawing:—

Fig. 1 is a circuit diagram of one embodiment suitable for illustrating the purpose and method of operation of the invention:

Figs. 2 to 4 are circuit diagrams of three other embodiments of the invention.

Referring to Fig. 1, 10 indicates a thermionic valve arranged as a grid-leak rectifier and having an oscillatory input circuit 11, 12 fed by any known means and an output circuit comprising a high-frequency choke 13 in series with the primary 14 of a low-frequency coupling transformer forming part of a subsequent amplifier 15; the latter (or the transformer) is designed in known manner to give greater amplification to the higher frequencies than to the lower frequencies fed thereto and hereinafter will be referred to as the tone correcting amplifier. This amplifier, then, has a rising amplification characteristic.

Reaction feed-back to the input circuit is pro-

vided by means of a reaction coil 16 in series with an adjustable or pre-set condenser 17 connected between the anode and the cathode (or earth line) of the valve 10, the control of reaction or selectivity of the input circuit being effected by means of a second shunt path for the high-frequency output component comprising a variable condenser 18 in series with the usual high-frequency by-pass condenser 19 also connected between the anode and cathode of the valve 10. The condenser 18 is provided with means as indicated at 20 for the short-circuiting thereof at its maximum capacity setting.

In operation, during the reception of a strong signal such as that emanating from a local station, when normally no reaction will be applied to the input circuit 11, 12, which will then be broadly tuned, the condenser 18 will be set at maximum capacity in order to provide a low impedance shunt, and thus prevent high frequency energy from passing around the reaction coil 16. When in this position the condenser 18 is short-circuited at contacts 20, and as a result the by-pass condenser 19 is placed directly across the input transformer of the tone correcting amplifier 15, thus to achieve a high-note loss, which by suitable choice of capacity of the condenser 19 can be made to equal the amount of high-note gain subsequently effected by the tone correcting amplifier 15.

When reaction is applied to the input circuit 11, 12 such as is necessary for the reception of a weak signal, that is, when the input circuit is sharply tuned or highly selective, considerable high-note loss is caused, but by reason of the adjustment of the condenser 18 to effect a decrease in the capacity thereof in order to obtain the said reaction, the short circuit by way of contacts 20 is removed from around the condenser 18. The by-pass condenser 19 is thus rendered less effective and the high-note gain of the amplifier 15 acts to compensate for the losses involved by the use of reaction.

As the resultant capacity of the condensers 18 and 19 in series, and thus also the high-note loss occasioned thereby, decreases in accordance with the amount of reaction applied to the input circuit 11, 12, or with its degree of selectivity, it is obvious that the high-note gain of the amplifier 15 becomes more and more effective to compensate for the high-note loss occasioned by the increased use of reaction.

In the modified arrangement of the circuit shown in Fig. 2, the thermionic valve 10 has an oscillatory input circuit 11, 12 and output circuit 55

comprising choke 13 and transformer primary 14 as previously described with reference to Fig. 1. The reaction coil 16 coupled to the input circuit 11, 12 has its ends connected, one to each of the fixed elements 21^a, 21^b of a differential condenser 21. The moving element 21^c of the said condenser is connected to the cathode (or earth line) of the valve 10.

The differential condenser 21 is so arranged that when set in one maximum position, i. e. with the entire moving element 21^c in register with the fixed element 21^a and clear of the other fixed element 21^b, the moving element 21^c is electrically connected with the opposing fixed element 21^a by way of contacts 22. A fixed condenser 23 is connected between the anode of the valve 10 and the fixed element 21^a of the condenser 21.

In the operation of this embodiment of the invention, during the reception of a strong signal without the use of reaction the condenser 21 is set with the moving element 21^c in register with the fixed element 21^a and electrical connection is made between them by way of the contacts 22. This has the effect of isolating the reaction coil 16 and at the same time places the condenser 23 as a shunt directly across the input transformer of the amplifier 15; thus, as previously described with reference to Fig. 1, a high-note loss is effected for subsequent correction by the characteristics of the amplifier 15.

When the differential reaction condenser 21 is adjusted to apply reaction to the input circuit 11, 12 the moving element 21^c is so placed that it is at least partly in register with the fixed element 21^b and some high-frequency energy is fed to the input circuit 11, 12 by way of the condenser 23, coil 16 and condenser elements 21^b, 21^c.

The connection between the condenser elements 21^a and 21^c having been broken, the high-note loss caused by the condenser 23 is reduced and the high-note gain of the amplifier 15 acts to compensate for the loss occasioned by the increased use of reaction.

The two parts of the differential condenser may be of unequal capacity for the purpose of obtaining a graduated degree of high-note loss.

In the embodiment shown in Fig. 3 the reaction-control condenser 17 is mechanically coupled ("ganged") to a variable condenser 24 shunted across the transformer 14, the condenser 24 taking the place of the condensers 18, 19 in Fig. 1. In Fig. 4 a similar system is shown, the only difference from Fig. 3 being that the condenser shunt is replaced by a shunt path comprising a variable resistance 25 ganged to the condenser 17 and a fixed condenser 26.

Although the thermionic valve 10 is shown in the drawing as a leaky-grid detector provided with capacity-controlled reaction and transformer coupling to the succeeding amplifier, it is obvious to those skilled in the art that various modifications involving other methods of rectification, reaction and coupling arrangements may be made without departing from the scope

of the invention, as defined in the appended claims. Moreover, the invention may be applied at a different stage of a wireless set.

Having now particularly described and ascertained the nature of my said invention and in what manner the same is to be performed, I declare that what I claim is:

1. In a radio receiver, an electron discharge tube provided with a tunable signal input circuit, an output circuit connected to the output electrodes of said tube, a network following said tube adapted to amplify the modulation frequencies of received signals, said network having a rising frequency-amplification characteristic, means operatively associated with said tube for regulating the selectivity characteristic of said signal input circuit, and additional means, operative upon adjustment of said first means to impart minimum selectivity to said tuned input circuit when a strong signal is received, for diverting from the input to said network currents of the higher modulation frequencies.

2. In a system as defined in claim 1, said electron discharge tube having included in its input circuit means for rendering the tube operative as a signal detector.

3. In a system as defined in claim 1, said first means including an adjustable signal frequency coupling path between the input and output circuits of said tube.

4. In a system as defined in claim 1, said additional means including an attenuation path connected to attenuate the higher modulation frequencies, said path being connected across the input of said network.

5. In a radio receiver, an electron discharge tube provided with a tunable signal input circuit, an output circuit connected to the output electrodes of said tube, means connected to the input circuit of said tube for rendering the tube operative as a signal detector, an audio amplifier network coupled to the output circuit of said detector tube, said network having a characteristic such that it has a rising modulation frequency amplification characteristic, a signal coupling path connected between the input and output circuits of said detector tube and including an adjustable condenser for regulating the degree of coupling, and a path connected across the input of said audio amplifier network for transmitting the higher modulation frequencies, the last path including an adjustable transmission control element.

6. In a system as defined in claim 5, said transmission control element comprising a variable condenser arranged to be simultaneously operative with the adjustable condenser of said signal coupling path.

7. In a system as defined in claim 5, said transmission control element consisting of a variable resistor arranged to be simultaneously operated with said adjustable condenser of the signal coupling path.
